UNITED STATES PATENT OFFICE.

WILLIAM B. JONES, OF NEWTON, ILLINOIS, ASSIGNOR TO HIMSELF AND
SUMNER B. MARSHALL, OF SAME PLACE.

WEATHER-STRIP.

SPECIFICATION forming part of Letters Patent No. 239,049, dated March 22, 1881.

Application filed June 22, 1880. (Model.)

To all whom it may concern:

Be it known that I, WILLIAM B. JONES, of Newton, in the county of Jasper and State of Illinois, have invented a new and Improved 5 Weather-Strip, of which the following is a specification.

The object of this invention is to provide a weather-strip and adjusting device especially designed for application to the bottoms of doors.

The invention consists of a hinged weather-strip secured on a door, near the bottom thereof, in combination with adjusting-blocks secured on the door-jamb and on the floor of the 15 room, as hereinafter set forth.

Figure 1 is a front elevation of a section of a door and door-frame, showing part of the combined device attached. Fig. 2 is a transverse section of door-frame and door, showing 20 the combined devices in position. Fig. 3 is a vertical sectional elevation on line $x-x$, Fig. 2, showing the door in the act of closing. Fig. 4 is a vertical sectional elevation on line $x-x$, Fig. 2, showing the door closed.

25 Similar letters of reference indicate corresponding parts.

In the drawings, A represents a door-frame, and B a door hinged thereto.

C represents the floor of a room, and D is 30 a semicircular flat block fastened on the floor C, at the rear end of the door-sill B' and flush with the top thereof.

E is the weather-strip, consisting of two strips, a b , hinged together longitudinally, so 35 that when the strip a is nailed upon the door B, as shown, the strip b hangs downward on an incline in contact with the sill B', and the joint between the two strips a b is covered by the hinge thereof, so that no rain can enter 40 said joint from above.

F is a block or button pivoted by a screw or pin, d , on the door-jamb G in such a position that the weather-strip E must come in contact

with its beveled edge when the door B is being closed, and be thereby pressed down in 45 close contact with the sill B'; and said block or button F has a curved slot, g , made through it above its pivoting-point, through which slot g is passed a pin, h , into the door-jamb G to prevent excessive movement of said block or 50 button F, as otherwise said block F might swing horizontally and interfere with the closing of the said door B. On opening and closing the door B, the lower edge of the weather-strip E is supported by the block D and thereby carried clear of the carpet. On closing 55 said door B the face of the weather-strip E at its outer end shuts against the adjustable block F, and said weather-strip E is thereby forced down on the door-sill B', and is bound 60 tightly on the door, thereby making it impossible for water to be driven in or about said weather-strip E.

It will be seen that this device operates without springs, and therefore is more durable than 65 those having springs, which springs become weak from constant use; and it will be seen that the block F forms a water-tight joint at point of contact with the strip E, so that this weather-strip, combined with the block F, perfectly fulfills its functions.

Having thus described my invention, what I claim as new, and desire to secure by Letters Patent, is—

1. The block F, pivoted on the door-jamb, 75 having a curved slot, g , above the pivoting-point, in combination with the jamb G and pin h , as and for the purpose specified.

2. The combination, with the weather-strip E, of the fixed block D and pivoted block F, 80 door B, and door-frame A, substantially as herein shown and described.

WILLIAM B. JONES.
